(57) **CLAIM**

(**) Term: **14 Years**

The ornamental design for a surface configuration of a ceiling panel for an airplane, as shown and described.

DESCRIPTION

This application is related to co-pending application Ser. No. 29/133,534, of the inventors, filed on even date herewith and entitled "Surface Configuration of the Interior Passenger Cabin of an Airplane."

FIG. 1 is a perspective view of a surface configuration of a ceiling panel for an airplane according to our novel design; and,

FIG. 2 is a front view of the surface configuration of a ceiling panel for an airplane according to our novel design. The dash lines included depict environment and are not part of the claimed design. Also enclosed is a set of photographs of an embodiment of our invention.
